UNITED STATES PATENT OFFICE.

JOHN A. DIESEL, OF CHICAGO, ILLINOIS.

CAN-TESTER.

No. 808,145.

Specification of Letters Patent.

Patented Dec. 26, 1905.

Application filed September 6, 1904. Serial No. 223,415.

To all whom it may concern:

Be it known that I, JOHN A. DIESEL, a citizen of the United States, and a resident of Chicago, county of Cook, and State of Illinois, 5 have invented certain new and useful Improvements in Can-Testers, of which the following is a specification, and which are illustrated in the accompanying drawings, forming a part thereof.

10 This invention relates to a device for testing tin cans as a step in their process of manufacture for the purpose of determining if the soldering of the joints has been so performed that the can is capable of being made air-tight 15 by closing the end left open for filling.

The invention contemplates means for receiving a can and securing it between a pair of clamping members, connecting its interior with a supply of air under pressure, submerging 20 it temporarily in a bath which will permit of the observation of air escaping from the can in case it leaks, and after bringing it out of the bath shutting off the supply of air and separating the clamping members, so that the 25 can will be discharged at either one of two discharge-points, depending upon the setting by the attendant of a movable cam-engaging roller.

The object of the invention is to provide a 30 machine which shall have the capacity to test a large number of cans in a given time, which will prevent the escape of air from the cans having sound joints while submerged, and which will separate the sound cans from the 35 defective ones with the least manual labor. These objects are obtained in the construction and arrangement of parts hereinafter described and which are illustrated in the accompanying drawings, in which—

40 Figure 1 is a detail central vertical section of the machine. Fig. 2 is an inclined plan of the same, having certain parts broken away to facilitate illustration. Fig. 3 is a plan view similar to Fig. 2, but having some of the 45 upper parts of the machine removed. Fig. 4 is an inclined front elevation, partly in section. Fig. 5 is a detail vertical section on the line 5 5 of Fig. 2. Fig. 6 is a plan, partly in section, of the parts shown in Fig. 5. Fig. 50 7 is a detail side elevation of the machine with some of the parts broken away. Fig. 8 is a plan, partly in section, of the parts shown in Fig. 7. Fig. 9 is a detail vertical section on the line 9 9 of Fig. 8. Fig. 10 is a detail 55 elevation showing some of the parts of Fig.

9 in a different position, and Fig. 11 is a sectional detail taken on the line 11 11 of Fig. 4.

Clamping members for receiving the can are preferably placed near the circumference of a wheel revolving in a plane inclined from 60 the horizontal, so that a segment thereof may be always submerged in a tank of liquid set under its lower side. The clamping and release of the cans are obtained by means of suitable cams fixed upon a frame arching over 65 the wheel and operating upon the cam-engaging rollers carried by one of the clamping members. The differential release of the cans providing for separating the defective from the sound ones is dependent upon shifting the 70 position of certain of the cam-engaging rollers by an attendant who observes the cans as they pass through the bath.

The machine is preferably mounted upon an inclined platform (shown at 25) to which 75 is bolted a suitable standard 26, providing bearings for the main driving-shaft 27 and the revolving stud 28, carrying at its base the worm-wheel 29, meshing with a corresponding worm 30 on the driving-shaft 27. The stand- 80 ard 26 is formed above into a tubular post 31, having an annular flange 32, to which is bolted a circular table 33. This table has an up- 85 standing continuous rim 34, which serves as a track for supporting the revolving parts of the machine, and is provided at the ends of its horizontal diameter with wings 35 36, Figs. 3 and 4, which support a pair of parallel straps 37 and 38, arching over the machine.

The revolving parts of the machine com- 90 prise besides the stud 28, previously mentioned, a wheel composed of the drum 39, forming the hub, rigidly secured to the stud 28, and a plurality of apertured sector-plates 40, Fig. 2, secured to the drum and forming 95 the spokes and rim of the wheel, the clamping members, and other mechanisms carried by the wheel. Each sector-plate 40 has a segmental depending rib 41 on its under face, to which are rotatably secured, as by means 100 of the bolts and cotter-pins 42, a plurality of rollers 43, which run on the track 34. Preferably a vertically-slotted aperture 41^a is formed in the rib 41 for receiving the bolt 42, and in this slot the bolt is adjust- 105 ably secured by a nut and washer 42^a, as most clearly shown in Figs. 7 and 11. A set-screw 43^a is provided for vertically adjusting the bolt, so that all of the rollers 43 may be made to engage the track 34. Extending radially 110

- from the drum 39 and communicating with its interior are a plurality of pipes 44, each provided with a valve 45 and each valve 45 controlled by the bell-crank 46 on its stem. 5 Couplings 47 connect each pipe 44 to the hollow shank 48 of a platen 49, rigidly secured in position by means of a clamp 50, encircling its shank and bolted to the sector-plate 40. The face of the platen 49 is covered with a 10 thick cushion 51, of some pliable material, such as rubber, and is centrally apertured at 52 to form an outlet-opening for the passage in the shank 48. A reciprocating plunger 53 coacts with the platen 49 to secure the can. 15 This plunger has a shank 54 running in ways 55, formed on the sector-plate 40, and carries an upstanding lug 56, upon which is mounted a cam-engaging roller 57.
- A latch or detent 58 is pivoted at 59 in lugs 20 60, rising from the ways 55, and has a toe 64, which falls behind a shoulder 65, formed on the plunger-shank 54, Figs. 9 and 10, so as to lock the plunger in its advance position. The latch 58 is provided with an upstanding stem 25 carrying a cam-engaging roller 61. This roller is supplemented by an oscillating arm 62, pivoted on the stem and having a lateral pin upon which is carried a roller 63, bearing against the face of the roller 61. This arm 30 may be manually swung so as to make contact with the cam provided for tripping the latch, and it has an extension 66, adapted to contact with a suitable trip 85 for swinging the arm out of action. A pin 58^a, set transversely in the stem of the latch 58, serves both 35 to hold the arm 62 to its seat and also as a stop for limiting the movement of the arm and adapted to be engaged by a stud 62^a, rising from the arm.
- 40 Each sector-plate 40 is apertured, as shown at 67, so as to allow a can X to drop through it when released by the retraction of the plunger 53. This aperture may be temporarily closed by a trough-shaped swinging gate 69, 45 (most clearly shown in Fig. 5,) hinged to the sector-plate 40 at the advance side of the aperture 67 and normally swinging free. A cam-strap 70, secured to the rim 34 of the table 33, rises in the path of the gate, and the latter, engaging it by a depending boss 69^a, is closed just before it reaches the feed-chute through which the cans are delivered to the machine. The length of the cam-strap 70 is such that the gate is held closed, the boss 69^a 50 riding upon the strap until the can resting upon it is engaged by the plunger 53.
- Suitable cams are provided for sliding the plunger 53 and for rocking the latch 58. All 55 of these cams are carried by the straps 37 and 38, those for actuating the plunger 53 being shown at 71, 72, and 73, while those rocking the latch 58 are shown at 74 and 75. The cams 71 and 72 are made preferably of a short-length angle-bar rigidly secured at an angle to the under face of the straps 37 and 65 38. The cam 73 is made of spring metal and attached at one end only, this attachment being shown as made to the strap 37.
- For tilting the latch 58 so as to bring the toe 64 into engagement with the shoulder of 70 the plunger 53 as the latter is advanced a yielding cam action is preferred. This is obtained by pivoting the cam 74, Fig. 6, to a cross-bar 76, secured to the upright portion of the straps 37 and 38, and providing a 75 spring 77 for controlling its free end. The latch is turned back so as to allow the plunger 53 to move in the slideways 55 by means of the cam 75, Fig. 8, which is preferably made of a relatively longer length of angle-bar and is secured to the under face of the straps 37 80 38.
- Compressed air is supplied to the drum 39 through the pipe 78, Fig. 1, entering the drum at its center through a stuffing-box 79. 85 The valves 45 are automatically operated by means of two arms 80 and 81, rigidly secured to the straps 37 and 38 and each having a finger 82 and 83 depending in the path of the valve-cranks 46, Fig. 4.
- The operation of the machine is as follows: Power is applied to the driving-shaft 27 in any way, such as by means of a belt over a pulley A, and a tank of hot water B is placed under the low side of the machine, so that a 90 segment of the revolving wheel and a part of the table 33 are submerged. As viewed in Fig. 2, the front of the wheel moves from left to right, and the cans to be tested are fed to the machine with their open ends toward the center, preferably through a chute C. The gate 69 for closing the aperture 67 is maintained in a horizontal position by the cam 70 beneath the chute, so as to receive the can and support it until it is clamped between 95 the platen 49 and the plunger 53 by the advance of the latter, produced by the cam 71 operating on the roller 57 and the tilting in of the latch 58, caused by pressure of the cam 74 upon the roller 61. As the wheel revolves 100 the gate 69 will pass off the supporting-cam 70 and swing downwardly, leaving the can supported only by the clamping members. When the valve 45 passes under the arm 80, the finger 82 will engage the crank 46 and open 105 the valve by giving it a quarter-turn, allowing the compressed air to rush into the can. As the can passes through the water if no air-bubbles are seen rising from it no further notice will be given to it by the attendant, and 110 when it has been carried out of the bath the supply of compressed air will be automatically shut off by a quarter-turn of the valve 45, produced through the contact of its crank 46 with the depending finger 83. The can 115 will later be discharged from the machine by being allowed to drop through the aperture 67 into a suitable chute (not shown) when it

has reached the position shown at the extreme left in Fig. 8. In this case—*i. e.*, when the can has proved to be sound by the non-appearance of bubbles of escaping air as it passed through the bath—the discharge of the can as just described is provided for in its release by the clamping members, which are operated as follows: The latch 58 is tilted outwardly by contact of its cam-engaging roller 61 with the 5 cam 75, and the plunger 53 is moved in the slideways 55 by contact of the roller 57 with the cam 72. The cam 75 is made of considerable length, Fig. 8, for the purpose of retaining the latch 58 in a tilted position until 10 the shoulder 65 on the shank of the plunger 53 has cleared its foot 64. If as the can passes through the testing-bath bubbles are observed, caused by the escape of air from any of its seams, the attendant will rotate the arm 15 62, so as to bring the supplemental roller 63 in front of the roller 61. In this case the locking member 58 will be tilted much sooner by the cam 75, the forward end of the cam being more sharply inclined, as shown at 75^a, 20 than its remaining portion to promptly effect this action, and the defective can Y will be released by the receding of the plunger 53, caused by the pressure of the yielding cam 73 upon the roller 57, and will be discharged by 25 dropping through the aperture 67 when at the position shown in Fig. 8, beneath which a suitable crate D will be placed to receive it. The wing 36 of the table 33 is recessed, as shown at 82, Fig. 3, to allow the defective can 30 to pass. As the arm 62 passes by the stop 85 the roller 63 will be moved to an inactive position beside the roller 61.

The machine as organized and shown has about thirty radial pipes 44 leading from the 35 drum 39, each being connected to a set of clamping members, as described. It is proposed to run the machine at a speed of two or three revolutions per minute, so that approximately five thousand cans will be tested per 40 hour. It will be understood from the preceding description and from the drawings that the cans are carried by the inclined wheel for only slightly more than a half-revolution, the clamping members remaining separated during 45 the half-revolution in which they pass the elevated side of the machine preliminary to receiving a can when they arrive at the position shown in Fig. 6. The chute C will receive cans so as always to contain a considerable 50 number one above another. As the machine revolves each pair of clamping members will carry away the lowest one in the chute, thus allowing those remaining to descend and the next lowest to fall onto the face 55 of the wheel, upon which it will slide or roll until the next aperture 67 comes under the chute. It will then drop onto the gate 69 and be secured and carried away by the corresponding pair of clamping members.

I claim as my invention—

55

1. In a can-testing machine, in combination, a stationary frame; a table rotatably mounted on the frame; an air-chest carried by the table; radiating tubular arms leading from the chest each having a clamping-head at its end; 70 a reciprocating clamping-head mounted on the table in line with each of the first-named heads; cams carried by the frame for actuating the reciprocating heads; an oscillating detent co-operating with each of the last-named heads; 75 and cams mounted on the frame for actuating the detents.

2. In a can-testing machine, in combination, a stationary frame; a rotatable table mounted thereon; co-operating clamping-heads carried 80 by the table, one thereof being fixed and the other reciprocating; an oscillatory detent for engaging the reciprocating head when advanced; a cam fixed obliquely across the orbital path of the detent; a member carried by 85 the detent and movable thereon before the face thereof which engages the cam.

3. In a can-testing machine, in combination, a stationary frame; a rotatable table mounted thereon; a pair of clamping-heads mounted on 90 the table, one thereof being reciprocatory; a detent for locking the movable head in its advanced position; a cam mounted on the frame for throwing back the detent; a member carried by the detent and movable in front of its 95 cam-engaging face; and a yielding cam carried by the frame for actuating the movable head.

4. In a can-testing machine, in combination, a stationary frame; a rotatable table mounted thereon; a pair of clamping-heads mounted on 100 the table, one thereof being reciprocatory; a detent for engaging the latter head when advanced; a cam mounted on the frame for throwing back the detent; a member carried by the 105 detent and movable in front of its cam-engaging face; a trip swinging such member away from the cam-engaging face of the detent; and a yielding cam carried by the frame for actuating the movable head.

5. In a can-testing machine, in combination, 110 a stationary frame; a rotatable table mounted thereon and having an aperture; a pair of clamping-heads carried by the table over the aperture; a chute leading to the heads; a swinging gate pivoted to the under side of the table 115 adjacent the aperture; and a cam fixed to the frame for closing the gate when the aperture is in line with the chute.

6. In a can-testing machine, in combination, 120 a stationary frame; a rotatable table mounted thereon and having an aperture; a pair of clamping-heads carried by the table over the aperture; a chute leading to the heads; a swinging gate pivoted to the under side of the table 125 adjacent the aperture and having a concave face; and a cam fixed to the frame for closing the gate when the aperture is in line with the chute.

7. In a can-testing machine, in combination, a stationary frame; a rotatable table mounted thereon; a pair of clamping-heads carried by the table, one thereof being reciprocatory; a cam mounted on the frame for engaging the movable head to advance it; an oscillatory detent for locking the movable head in its ad-

vanced position; and a yielding cam mounted on the frame for throwing the detent into action.

JOHN A. DIESEL.
